DESIGN FOR A RESPIRATOR

Howard B. Lewis, Los Angeles, Calif., assignor to
B. F. McDonald Company, Los Angeles, Calif.,
a corporation of California

Application July 8, 1938, Serial No. 78,358

Term of patent 14 years

To all whom it may concern:

Be it known that I, Howard B. Lewis, a citizen of the United States, residing at Los Angeles, in the county of Los Angeles and State of California, have invented a new, original, and ornamental Design for a Respirator, of which the following is a specification, reference being had to the accompanying drawing, forming a part thereof.

Fig. 1 is a perspective view looking from the

front and top of a respirator embodying my new design, Fig. 2 is a side elevational view thereof with a portion of the headstrap broken away for convenience of illustration, and Fig. 3 is a top plan view thereof with the headstrap entirely omitted.

I claim:

The ornamental design for a respirator, as shown and described.

HOWARD B. LEWIS.
